(57) **CLAIM**

The ornamental design for a controller grip, as shown and described.

DESCRIPTION

FIG. 1 is a top plan view of a controller grip showing my new design;
FIG. 2 is a bottom plan view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a rear perspective view thereof;
FIG. 8 is a top plan view showing two game console controllers installed on the controller grip; and,
FIG. 9 is a bottom plan view showing two game console controllers installed on the controller grip.
The broken lines indicate disclaimed portions and form no part of the claimed design.
